UNITED STATES PATENT OFFICE

GEORGE H. MAGRATH, OF WHITINSVILLE, MASSACHUSETTS

BOBBIN CLUTCH

Application filed August 27, 1928. Serial No. 302,204.

This invention relates to a clutch for securing a bobbin or other weft carrier on a spinning or twisting spindle.

The objects of my present invention are to provide a clutch formed of a minimum number of parts and to provide a construction which shall be yieldingly self-centering, which will accommodate itself to slight variations in the diameter of the bobbin recess, which may be easily and economically manufactured, and which comprises very few and simple parts which may be readily assembled.

Other objects of the invention will appear hereinafter.

Reference is to be had to the accompanying drawings in which

Fig. 1 is a side elevation of a spindle having a preferred form of my bobbin clutch applied thereto, and shown in central section;

Fig. 2 is an elevation of the casing member;

Fig. 3 is a plan thereof.

I have shown a spindle having a blade 10 and whirl 11 on which a bobbin B is mounted. The whirl 11 has a recess 12 in its upper face for a purpose to be described.

A cap or casing member 14 is mounted on the blade 10 at a substantial distance above the whirl 11 and its lower end is seated in the recess 12.

The casing member is preferably forged from a single blank of spring steel, and comprises an integral cylinder 21 and driving fingers 22.

The cylinder is cut along its sides to form the vertical driving fingers 22 which are integral with it near the bottom and free at the top. The fingers 22 are bent or offset to the outlines shown in Fig. 2. The cylinder 21, will extend straight upward around the axis of the spindle from the recess 12 in which its lower end fits. The offset upper ends 28 of the fingers 22 engage the inside surface of the passage in the bobbin. They are sprung outwardly and are held under spring tension.

It will thus appear that my improved bobbin clutch comprises only a single piece, the

member 14, and that there are no movable parts except the spring centering fingers 22, which have a slight swinging movement at their upper ends.

When a bobbin is placed on the spindle, as indicated in Fig. 1, the bobbin is centered by the fingers 22 and recess 12, as well as by the head of the casing 14. The driving fingers 22 yieldingly engage the inner wall of the bobbin and form effective driving contact therewith.

A bobbin clutch thus formed has no parts capable of displacement or mal-adjustment and is particularly well adapted for the purposes intended. Being formed in one piece it can be made easily by well known methods and none of its parts have to be fitted together, so all of them are produced in exactly the same form. The smooth outer faces of the fingers 22 make it easy to dislodge and remove bunches of yarn wound thereon.

Having thus described my invention and the advantages thereof, I do not wish to be limited to the details herein disclosed, otherwise than as set forth in the claims, but what I claim is:

1. A bobbin clutch for a spindle having a blade and whirl, said clutch comprising a cylindrical part and a head, the cylindrical part having fingers yieldingly movable inwardly to a point within the cylindrical part at their upper ends and being normally projected outwardly beyond said cylindrical part at points below their upper ends to engage the inner surface of a bobbin.

2. As an article of manufacture, a bobbin clutch consisting of a single piece of thin spring steel comprising a cap perforated at the center to receive the blade of a spindle and having a cylindrical portion extending below to be seated in a recess in the whirl and having driving fingers extending upwardly from the bottom and projecting beyond the cylinder to engage the bobbin.

In testimony whereof I have hereunto affixed my signature.

GEORGE H. MAGRATH.
